(57) **CLAIM**

The ornamental design for a work glove, as shown and
described.

DESCRIPTION

FIG. 1 is a perspective view of a first embodiment of the
work glove in accordance with the present invention;
FIG. 2 is a plan view of the work glove of FIG. 1;
FIG. 3 is a perspective view of a second embodiment of the
work glove in accordance with the present invention;
FIG. 4 is a plan view of the work glove of FIG. 3;
FIG. 5 is a side view of the work glove of FIGS. 1 and 3;
FIG. 6 is a second side view of the work glove of FIGS. 1
and 3;
FIG. 7 is a first end view of the work glove of FIGS. 1 and
3; and,
FIG. 8 is a second end view of the work glove of FIGS. 1
and 3.
The broken lines illustrate portions of the work glove and
form no part of the claimed design.
